UNITED STATES PATENT OFFICE.

ERNEST BRIGHT ROLLASON, OF SYDNEY, NEW SOUTH WALES, AUSTRALIA.

ORNAMENTAL HAIR-COMB.

1,305,309.

Specification of Letters Patent. Patented June 3, 1919.

Application filed July 29, 1915. Serial No. 42,508.

To all whom it may concern:

Be it known that I, ERNEST BRIGHT ROLLASON, subject of the King of Great Britain and Ireland, residing at 121 Castlereagh street, Sydney, New South Wales, Australia, have invented new and useful Improvements in Ornamental Hair-Combs, of which the following is a specification.

It is well known that many devices have been invented for preventing hair-pins from falling from the hair of the wearer when they have been installed in the usual way.

This invention consists in returning at an acute angle and obliquely, one of the legs of an ordinary plain hair-pin. The returned part will effectually prevent the pin or the comb from dropping out from the hair.

In the accompanying drawings, forming part hereof, is illustrated a form of embodiment of the invention, and in which:

Figure 1, is a front elevation of a hair-pin with the returned point of one of the legs.

Fig. 2, is an edge elevation of the same.

Fig. 3, is an end view of Fig. 1.

It may be mentioned that many experiments have been made with various devices to secure the end sought. If both points of a hair-pin be turned over, much difficulty will be experienced in releasing it; if the turned over part be located intermediately between the points and the bend, on either one or both legs of the hair-pin, it will be easy to insert the pin in the hair, but almost impossible to withdraw it, but with only one point turned up, the pin may be readily inserted and withdrawn.

Having thus fully described my invention, what I claim as new and desire to secure by Letters Patent is:

1. A hair pin constructed of a single 40 length of resilient material and comprising a pair of legs of unequal lengths, and a connecting bend, said legs being spaced apart in parallelism and disposed in the same plane, the long leg of the said two legs having the 45 end thereof bent outwardly and rearwardly at an acute angle to provide a return bend or hook, said return bend or hook being disposed in a plane oblique to the plane of said legs and adapted to engage the hair to retain 50 the hair pin therein and arranged to be disengaged by a rotative movement of the hair pin to release the latter readily without breaking the hair.

2. A hair pin constructed of a single 55 length of resilient material and comprising a pair of straight parallel legs or prongs and a connecting bend, a single leg or prong only of the hair pin being provided with an exteriorly arranged return bend adapted to engage the hair to retain the hair pin therein and arranged to be disengaged by a rotative movement of the hair pin to release the latter readily without breaking the hair.

In testimony whereof I have signed my 65 name to this specification in the presence of two subscribing witnesses.

ERNEST BRIGHT ROLLASON.

Witnesses:

A. MOSSER,
H. C. CAMPBELL.
